UNITED STATES PATENT OFFICE.

FRANK W. SMITH, OF PORTLAND, MAINE, ASSIGNOR OF ONE-FOURTH TO
FREDERICK O. CONANT, OF SAME PLACE.

APPARATUS FOR STERILIZING CANNED GOODS.

SPECIFICATION forming part of Letters Patent No. 628,554, dated July 11, 1899.

Application filed April 16, 1897. Serial No. 632,432. (No model.)

To all whom it may concern:

Be it known that I, FRANK W. SMITH, a citizen of the United States, residing at Portland, in the county of Cumberland and State of Maine, have invented certain new and useful Improvements in Apparatus for Sterilizing Canned Goods; and I do hereby declare that the following is a full, clear, and exact description of the invention, which will enable others skilled in the art to which it appertains to make and use the same.

It is the purpose of my invention to provide a convenient mechanism by means of which corn or other substances in hermetically-sealed cans or in other vessels may be subjected to the action of heat or steam while passing through a closed chamber, the contents of said cans or vessels being agitated as they pass from end to end of such chamber.

I have embodied my invention in the device shown in the drawings, in which—

Figure 1 is a side elevation, a portion of the wall of the cylinder being broken out to show the interior mechanism. Fig. 2 is an end view 25 of the same with a detail of the conveyer and cooler. Fig. 3 is a detail showing in section a portion of the device when the cylinder is placed on end, and Fig. 4 is a transverse section of the valve used with the modification 30 of the cylinder shown in Fig. 3.

The cooking-chamber is an air-tight or steam-tight cylinder A, mounted upon proper supports B B. Passing through its center from end to end is a shaft a, supported in proper journals b b in either end of the cylinder A. Outside the cylinder the shaft carries at either end a sprocket-wheel c, and at one end the shaft is also provided with a beveled gear d, which matches with a smaller beveled 40 gear e on the shaft f, which is provided with a pulley g. Within the cylinder A and fixed to its walls is a spiral or worm h, which is shown in Fig. 1. Within the space not occupied by the spiral is a fluted cylinder k, which is fixed upon the shaft a, the space between the lower part of the flutings of the cylinder k and the inner edge of the spiral being slightly larger than the radius of the can or other vessel to be processed. Upon 45 the upper side of the cylinder, and preferably near the end at which power is applied, is a

conveying-chute, journaled in which are the two shafts m n, which carry within the chute the tapering or conical valves o and r, in each of which is a recess s, which when the machine is used for processing cans should be of depth and length sufficient to receive the cans. The end of the shaft m is threaded to receive the collar 1, which may be screwed on or off the shaft and retained in any position by means of the binding-screw 2. Between the collar 1 and the hub of the journal of the shaft m is placed a coil-spring 3. The office of this spring is to set the tapering valve o more firmly upon its seat, the tension 65 of the spring being controlled by adjusting the position of the collar 1. The shaft n is provided with a like collar and spring, the same being located near the smaller end of the conical valve r. The shafts m and n are 70 provided, respectively, with spur-gears p p', and the shaft n also carries the sprocket-wheel t, which is connected by a chain u with the sprocket-wheel c. A similar chute with similar valves is provided upon the under side of 75 the cylinder and at the opposite end. The upper portion of the upper chute connects with the conveyer v. There may be attached to the chute on the lower or under side of the cylinder a conveyer and cooler z', as shown 80 in Fig. 2.

w is a valve by which steam or heat may be admitted to the cylinder A, which may be also provided with a thermometer x and steam-gage y, such as are ordinarily used on process- 85 chambers.

As it is sometimes preferable to process certain substances with a vent in the can, in which case to avoid leakage of the contents an upright position of the can is necessary, a 90 modification of the device is shown in Figs. 3 and 4, the principal changes being that the cylinder is placed on end instead of upon its side, as shown in Fig. 1, and that the valve is also altered. The valve used is shown in 95 Fig. 4, having upon either side a recess for the admission of the can or vessel.

In order to subject all parts of the cans to the action of the heat or steam, the walls of the spiral and the flutings of the cylinder k 100 are perforated, as shown in Figs. 1 and 2.

The operation of the device is as follows:

Assuming the material to be cooked, processed, or kiln-dried to be contained in cans, they are fed by hand or otherwise into the conveyer *v* at the top of the cylinder *A*, whence 5 they are conveyed into the chute *l* and pass into the recess *a* in the upper valve *o*, which by rotation carries the can and drops it into the corresponding recess *s* in the valve *r*, which also is in rotation. From the last- 10 named recess the can is deposited in one of the flutings of the cylinder *k*, the upper edge of the segment of the can being within the spiral or worm *h*. The deposit of the next can from the valves *o* and *r* is so timed by 15 means of the rotation of the cylinder *k* and the valves *o* and *r* that it falls into the next fluting of the cylinder. As this process is repeated the spiral *h* as the cylinder is rotated carries the cans gradually toward the other 20 end of the cylinder until they reach the chute upon the under side thereof, when the cans are discharged by the valves in the lower chute by the reverse of the process at the upper chute. As the cans progress through 25 the cylinder steam or hot air, which is admitted through the valve *w*, thoroughly cooks or kiln-dries their contents, which are kept in a constant state of agitation by means of the rotation of the cylinder *k*.

30 The location of the inlet and outlet chutes may be varied. By suitable variation in the construction of the valves and fluted cylinder cans or packages of other than cylindrical form may be handled.

35 The capacity of the machine may be doubled by doubling the length of the chamber *A*, doubling the worm, and duplicating the valves: The capacity of the machine may also be increased or nearly doubled by fluting 40 the interior of the cylinder *k* and placing within the cylinder a worm or spiral, the latter being supported from a dead-center. In such case the cans or other packages to be treated may be admitted to and removed from 45 the interior flutings by means of slide or block valves in the ends of the chamber *A*.

What I claim is—

1. In a machine for processing food and other substances contained in cans or similar vessels, a hollow cylinder provided with a central shaft and means for rotating the same, said shaft carrying a fluted cylinder, a spiral or worm surrounding said last-named cylinder, an inlet at one end of the upper side and 50 an outlet at the other end of the lower side, steam-tight valves controlling said inlet and outlet together with means for operating said valves, substantially as described.
2. In an apparatus for processing food and other substances contained in cans or other vessels, a hollow cylinder having receiving and discharging ports, valves controlling said ports and means within said cylinder by which 55 said cans or other vessels are carried spirally

around said cylinder from one port to the other substantially as described.

3. The combination of a hollow cylinder having inlet and outlet ports, a spiral fixed to its inner walls, a fluted cylinder within said spiral, means for rotating said last-named cylinder and a steam or other heat supply communicating with said first-named cylinder, substantially as described.

4. In a machine for processing or drying goods, the combination of a steam-tight hollow cylinder provided with an inlet and outlet port, within said cylinder a cylinder having upon its surface devices for receiving and holding the vessels or packages to be processed, and guiding the same from end to end 75 of said last-named cylinder, means for rotating the last-named cylinder and a steam or heat supply connected with said first-named cylinder, substantially as described.

5. In a machine for processing or drying 85 goods, the combination of a hollow cylinder provided with a port or ports, within said cylinder a cylinder having upon its surface devices for receiving and holding the vessels or packages to be processed, means for rotating 90 said last-named cylinder whereby the said vessels or packages during a part or the whole of the revolution of said inner cylinder may be rotated upon their own axes as well as around said cylinder and a steam or heat supply 95 communicating with said first-named cylinder, substantially as described.

6. In a machine for processing or drying goods, the combination of a hollow cylinder provided with inlet and outlet ports and a 100 spiral fixed to its inner walls, a cylinder within said spiral having upon its surface devices for receiving and holding the vessels or packages to be processed while passing through the machine, means for rotating said last- 105 named cylinder whereby the said vessels or packages during a part or the whole of the revolution of said inner cylinder may be rotated and a steam or heat supply communicating with said first-named cylinder, sub- 110 substantially as described.

7. A retort or sterilizer for canned goods provided with inlet and outlet ports and a steam or heat supply, an inclosing cylinder, an inner fluted or recessed drum together with 115 means whereby the packages to be processed are carried around the inclosing cylinder and are rotated during part of the circumvolution and during the remainder of the circumvolution are supported by said drum, substan- 120 tially as described.

In testimony that I claim the foregoing as my invention I have hereunto set my hand this 14th day of April, A. D. 1897.

FRANK W. SMITH.
